FEELER-MOTION FOR LOOMS.

1,290,108.

Specification of Letters Patent.

Patented Jan. 7, 1919.

Application filed February 23, 1917. Serial No. 150,303.

To all whom it may concern:

Be it known that I, HARRY A. DAVIS, a citizen of the United States, residing at Hopedale, in the county of Worcester and State of Massachusetts, have invented an Improvement in Feeler-Motions for Looms, of which the following description, in connection with the accompanying drawings, is a specification, like characters on the drawings representing like parts.

The invention to be hereinafter described relates to looms, and more particularly to the feeler motions for effecting a change in the condition of the loom when the filling in the active shuttle becomes substantially though not fully exhausted.

Various forms of feeler mechanisms have heretofore been proposed, some of which depend for their action by measuring the thickness of the filling on the carrier or bobbin in the shuttle, others upon movement of the feeler in a direction longitudinally of the shuttle when the filling becomes substantially exhausted. Feeler mechanisms to be practically efficient must be sensitive, because on the one hand, when substantial exhaustion of filling is reached and only sufficient remains in the shuttle to make one, two, or more picks, the feeler must act to set in operation a train of mechanism to effect either replenishment of filling or loom stoppage, as the case may be, and on the other hand, it must not so act when sufficient filling remains in the shuttle for weaving purposes, otherwise, objectionable waste of filling will result.

An important feature of the present invention, therefore, consists in a feeler motion wherein the desired sensitiveness of the feeler may be maintained and yet the feeler be prevented from acting prematurely. This feature of the invention is carried into effect in the present instance by providing the feeler motion with a rotatable feeler which is locked from rotative movement until the filling reaches a predetermined degree of exhaustion, and is then unlocked, and in providing the feeler with an end portion which by engagement with the filling will prevent rotative or rocking movement of the feeler after it is unlocked until the filling is substantially exhausted.

It becomes necessary in many cases of

feeler looms, to adjust the feeler mechanism, and where the feeler operates through levers, rods and the like, to set in operation a train of mechanism, much difficulty is experienced in readjusting the connections. Another important feature of the invention, therefore, consists of a self-contained feeler mechanism and a flexible connection between it and the train of mechanism to be set in operation, so that adjustment of the feeler mechanism does not require change in the connections between it and the train of mechanism. This flexible connection is established in the present instance of the invention by a wire properly incased to prevent buckling when pushed lengthwise and having its end supported to be pushed when the feeler on a detecting heat indicates substantial exhaustion of filling.

The invention embodies various other novel features, which, together with those mentioned, will be hereinafter described in connection with the accompanying drawings showing one good, practical form thereof, and then defined by the claims.

In the drawings:—

Figure 1 is a plan view of one side of a loom showing sufficient parts with the invention associated therewith to make clear the construction and operation;

Fig. 2 is a side elevation indicating the parts shown by Fig. 1;

Fig. 3 is a plan view showing the feeler motion proper on an enlarged scale;

Fig. 4 is a side elevation of the parts shown by Fig. 3;

Fig. 5 is a section on the line 5—5, Fig. 3;

Fig. 6 is an enlarged detached plan view of the end portion of the actuator showing one means for controlling the operative relation between it and the operating member; and

Fig. 7 is a side view of the parts shown in Fig. 6.

The loom frame 1; the breast beam 2; the lay 3 having the shuttle-box 4 for the reception of the shuttle 5 in which is supported the filling carrier or bobbin 6; and the shipper stand 7 may all be of usual or any preferred construction. The front wall 8 of the shuttle-box and the front wall of the shuttle 5 may each be provided with an opening, as is common in feeler looms, for

the entrance of the feeler to feel for the filling in the shuttle when the lay makes its detecting beat.

Looms of the filling replenishing type 5 may effect replenishment of filling either by a change of shuttles or by changing the filling carrier or bobbin in the shuttle; and while the present invention is applicable to either type, the present instance of the 10 invention is shown as embodied in a loom wherein upon substantial exhaustion of the filling in the active shuttle, the old filling carrier or bobbin in the shuttle is ejected and a filling carrier or bobbin with a fresh 15 supply of filling is substituted therefor.

Mounted in suitable brackets 9 supported by the loom frame, is the transverse or change shaft 10 having secured thereto and extending upwardly therefrom, the arm 11, 20 Figs. 1 and 2. Pivoted mounted upon the arm 11 at 12 is the arm 13 which extends rearwardly for engagement by an operating member at times, as will more fully appear. The arm 13 may be hereinafter designated 25 as the actuator for the purposes of identification, because, by its forward movement, it turns the transverse or change shaft 10 to thereby initiate filling replenishment.

The self-contained feeler mechanism in 30 the present invention is adjustably secured to the machine frame in appropriate position to support the feeler for entrance into the shuttle to feel for the filling as the lay makes its detecting beat. In the present 35 form of the invention, the feeler stand 14 is adjustably mounted upon a bracket 15 by suitable securing means such, for instance, as the screw bolt 16, Fig. 1, which passes through an elongated slot 17 formed in a 40 flange projecting from the feeler stand. The bracket 15 may be adjustably secured to the loom frame or the shipper stand 7 by means of a bolt 18, the construction being such that the self-contained feeler mechanism 45 may be appropriately adjusted to enter the openings in the front wall of the shuttle-box and shuttle as the lay makes its detecting beat. Mounted for reciprocating movement in the feeler stand 14 is the feeler 50 slide 19, Fig. 3, having a stem 20 projecting forwardly therefrom and passing through a bearing 21 at the front of the feeler stand. The stem 20 at its front end portion is provided with a stop to limit the 55 rearward movement of the feeler slide under the impulse of the spring 22 which, in the present instance of the invention, is shown as of the coil type surrounding the stem 20 of the feeler slide. The stop referred to may be variously formed, but in 60 the present instance of the invention, is provided by a collar 23 preferably formed of a soft material such as leather, and held in place by a nut 24 threaded to the end of the 65 stem 20.

Rising from the rear portion of the feeler slide 19 is the projection 25, Figs. 3 and 4, through the lower portion of which extends the feeler or feeler member 26, the front end portion of the feeler member passing 70 into the hollow portion 27 of the stem 20. If desired, the feeler stem 20 may have fixed thereto a collar 28, Fig. 3, between which and the front portion of the feeler stand 14 is located the spring 22 normally 75 acting to hold the feeler slide in rearward position. Rearward of the collar 28, the feeler stand has rising therefrom a lug or bearing member 29, the lower portion of which has an opening therethrough serving 80 to guide the feeler 26 in its longitudinal movement relative to the feeler slide. The feeler 26 is normally under the influence of a spring tending to hold the feeler in its rearward position relative to the feeler slide 85 19, and in the present instance of the invention, this spring is of the coil type 30, preferably surrounding the feeler 26 and having one end resting against and secured to the projection or flange 29, and the other 90 end resting against and secured to the collar 31 which is itself adjustably mounted upon the feeler 26, the construction being such that the spring 30 normally acts to hold the feeler 26 in rearward position. 95

In one aspect of the present invention, it is contemplated that the feeler 26 shall be under the influence of means for turning the feeler about its longitudinal axis when on a detecting beat the filling has become substantially exhausted; and to this end the spring 30 may, in addition to its expansion qualities, have a torsional action upon the feeler 26 tending to rotate it when it is freed to such rotative movement. For this purpose, the ends 32 of the spring 30 may be engaged in appropriate recesses of the collar 31 and projection 29, substantially as indicated in Figs. 3 and 4.

The end of the feeler 26 is provided with 110 a filling engaging end portion 33 which, by engagement with the filling when a working supply is present in the shuttle, will prevent rotative movement of the feeler on a detecting beat, but which, when the filling has 115 reached substantial exhaustion, will no longer be able to restrain the feeler 26 from such rotative or rocking movement.

Secured to and extending from the feeler 26 is an arm 34 which, when the feeler is in its rearward position as indicated in Figs. 2, 3 and 4, is adapted to rest upon the top portion of a projection 35 adjustably secured to the feeler stand by means such as the screws 36. The projection 35 is preferably formed as indicated in Figs. 3 and 4, with an inclined portion 37 which, if the feeler 26 has been rotated or rocked upon a detecting movement of the lay, as it moves forwardly, will, as the feeler member returns 130

to rearward position, engage the arm 34 secured to the feeler 26 and perforce, cause the feeler 26 to be returned rotatably to its initial position. The arm 34 projecting from the feeler 26 extends outwardly from the feeler between the projection 29 and the collar 28 carried by the feeler slide, the construction being such that upon a detecting movement of the lay, when the filling-engaging end of the feeler is pushed forwardly, the spring 30 which may be somewhat lighter than the spring 22, will first be slightly compressed to relieve the collar 31 from frictional bearing against the projection rising from the feeler slide, so that in case the filling has become substantially exhausted, the feeler will not be restrained from rotative movement by the frictional engagement of the collar 31 and projection 25.

20 As the lay moves forward, the feeler slide will yield forwardly against the tension of the spring 22 and the feeler 26 will travel forwardly with it to carry the arm 34 forwardly beyond the top portion of the projection or cam piece 35, the construction being such that the arm 34 no longer holds the feeler from rotative movement when the arm 34 is carried forwardly beyond the projection 35.

25 As hereinbefore noted, it is desirable that the feeler shall be sensitive in order that when the filling has become substantially exhausted, on a detecting beat, it will readily ascertain this fact and be turned upon its longitudinal axis, but when made sufficiently sensitive for this purpose, it is liable to prematurely act during the weaving operation, and cause loss or waste of filling by indicating the change before the filling is substantially exhausted. The present invention, therefore, contemplates means for locking the feeler from such rotative or rocking movement until, as the filling is progressively unwound from the carrier or bobbin 45 in the shuttle, its diameter has become sufficiently decreased to permit the feeler member to enter farther into the shuttle on each detecting beat and then, while still a working supply of filling remains in the shuttle, 50 unlocking the feeler so that thereafter it shall be under control of the filling alone, and be prevented from rotative or rocking movement by engagement with the filling until substantial exhaustion.

55 Various means may suggest themselves for the accomplishment of the ends stated, but in the present instance of the invention, the hub portion 38 of the arm 34 projecting from the feeler 26 is provided with a recess 60 or groove 39, Fig. 5, which is adapted to be engaged by the end 40 of a rod 41 supported for longitudinal movement in the projections 25 and 29 carried by the feeler slide. The rod 41 preferably has its front end portion turned back upon itself as indicated in Fig. 3, the end 40 of the rod being held rearwardly in locking position with respect to the recess 39 in the hub 38 by means of a spring 42, one end of which bears against the rear face of the projection 29 and the other end against a collar 43 adjustably secured to the locking rod 41. Rearward of the projection 25, extending upwardly from the feeler slide 19 the locking rod has a head or contact portion 44 adapted to be struck by the front wall of the shuttle or the front wall of the shuttle-box when the feeler 26 enters the shuttle a predetermined amount. From the construction described, it will be noted that when a full bobbin is in the shuttle, the filling-engaging end of the feeler 26 will enter the shuttle on each detecting beat and contact with the filling, and upon further forward movement of the lay, the feeler member 26 will first be moved slightly forward to relieve the pressure of the collar 31 against the projection 25 and then the feeler slide and feeler will move forwardly in unison. When the filling in the shuttle has reached a predetermined degree of depletion, but before substantial exhaustion and the filling engaging end 33 of the feeler therefore enters farther into the shuttle, the engaging end 44 of the lock rod 41 will engage the front wall of the shuttle or shuttle-box or other convenient part carried by the lay, and move the lock rod forwardly, thereby unlocking the feeler to rotative movement. Should there still remain sufficient filling in the shuttle, however, to continue weaving, the feeler will be prevented from such rotative movement on each detecting beat of the lay by engagement of the end 33 of the feeler with the filling until the latter becomes substantially exhausted. When the filling reaches substantial exhaustion, however, it will no longer be able to hold the feeler from rotative movement under the action of the spring 30 and the arm 31, either or both, and the feeler will turn clockwise, viewing Fig. 5, as the lay continues its forward movement, thereby effecting initiation of replenishment as will now be described.

65 Mounted in the path of the arm 34 as it is moved forward when the filling has become substantially exhausted, is a plunger 45 supported for longitudinal movement in a casing 46 which may be appropriately secured to the feeler stand. The plunger 45 has a shouldered portion 47 which limits movement of the plunger rearwardly or to the left, viewing Fig. 3. Adjustably secured to the casing 46 is a guide tube 48 through which passes the wire 49, the end 50 of which rests against the front end portion of the plunger 45, Fig. 3, the construction being such that should the arm 34 engage the plunger 45 as the feeler moves forwardly after an indication of filling exhaustion,

tion, it will push the wire 49 lengthwise. In order that the wire 49 may be prevented from buckling when thus moved lengthwise, it is surrounded by a casing having an internal diameter substantially the same or only slightly greater than the diameter of the wire 49. In the present instance of the invention, the casing is formed of a wire coil 51 but obviously, the casing may be otherwise contrived, the essentials in this respect being that it serves to prevent buckling of the wire 49 when the latter is pushed lengthwise by the finger 34. In order that the guide tube 48 may be appropriately supported adjustably in the casing 46, it may be held therein by a suitable set screw or other convenient means 52.

Endwise movement of the wire 49 upon call for filling replenishment, is utilized in the present invention to bring into operative relation the actuator and its operating member, and to this end in the present instance of the invention, the actuator 13 has pivotally mounted thereon as at 53, Fig. 7, a dog 54, the end portion 55 of which is normally held out of the path of the operating member 56, Figs. 1 and 2, by a spring 57, preferably seated in a recess formed near one end of the actuator 13, and bearing against a shoulder of the dog 54, substantially as indicated in Fig. 7. Rising from the dog 54 is a projection 58 which bears against a plunger 59 supported by a casing 60 carried by the actuator 13. The plunger 59 is movable longitudinally in the casing 60 to an extent limited by the shoulder 61 formed in the interior of the casing, and against the end 62 of the plunger, the end 63 of the wire 49 bears, the construction being such that should the plunger 45, Fig. 3, be forced longitudinally to the right by the arm 34 of the feeler, when substantial exhaustion of filling has been indicated, the end 63 of the wire 49 will move the plunger 59, Fig. 7, to the left, thereby turning the dog 54 downwardly and carrying its end 55 into the path of movement of the operating member 56, which in the present instance of the invention, may be formed by a part 64 carried by the cam follower 65, Fig. 2, so that on forward movement of the operating member 56, the actuator 13 will be moved forwardly, thereby turning the transverse or change shaft 10 to initiate filling replenishment.

From the construction described, it will be apparent that the flexible connection between the feeler mechanism and the train of mechanism for initiating filling replenishment enables the feeler mechanism to be adjusted to various positions without the necessity for changing the construction, form, or dimensions of other rigid parts, and the flexible character of the connection between the feeler mechanism and the train of mechanism for initiating filling replenishment en-

ables the flexible connection to be carried, around various obstructing portions of the loom without interference therewith. In order that the movement of the dog 54 may be appropriately limited, it is provided with a projection 66, Fig. 7, which may move in an appropriate slot 67, formed in the end of the actuator 13.

In order to properly guide the wire or flexible connection 49 into cooperative relation with the plunger 59, Fig. 7, the casing 60 is provided with a guide tube 68 which may be similar in all respects to the guide tube 48 hereinbefore described, and may be held in adjusted position in the casing 60 by a suitable set screw 69, Fig. 7.

Ordinarily, it may not be necessary to connect the projection 29 with the collar 28 of the feeler slide between which parts the arm 34 is adapted to move, but in some cases it may be preferable in order to strengthen these parts and prevent relative movement of the projection 29 and collar 28 to brace them in separated relation by a finger or bar 70, Figs. 3 and 4.

What is claimed is:—

1. In a feeler motion for looms, the combination of a feeler having a filling engaging portion, means for rotating the feeler on its longitudinal axis when on a detecting beat the filling in the shuttle is substantially exhausted and restrained from effecting such movement when the feeler is in rear position, locking means for preventing rotative movement of the feeler until the filling reaches a predetermined degree of exhaustion and then freeing it to rotative movement, and means for initiating replenishment of filling when the feeler is rotated on a detecting beat.

2. In a feeler motion for looms, the combination of a feeler to feel for the filling in the shuttle on a detecting beat, means tending to rotate the feeler as the lay beats up, and a lock to prevent the action of said means until the filling is exhausted to a predetermined degree and then freeing the feeler to rotative movement, said feeler being prevented from rotative movement after it is unlocked by engagement with the filling until the filling is substantially exhausted, and means actuated by the feeler when the filling is substantially exhausted to initiate replenishment.

3. A feeler motion for looms, comprising, in combination, a feeler mounted for rotative movement about its longitudinal axis and prevented from such rotative movement by engagement of the feeler with the filling until the filling is substantially exhausted, a lock to prevent rotative movement of the feeler until the filling reaches a predetermined degree of exhaustion prior to substantial exhaustion and to then free the feeler that its rotative movement may be

- controlled by engagement with the filling, and means for changing the operative condition of the loom when rotative movement of the feeler is permitted by substantial exhaustion of filling on a detecting beat.
4. A feeler motion for looms, comprising, in combination, a feeler, means for rotating the feeler about its longitudinal axis, a lock for preventing rotative movement of the feeler until the filling has been exhausted to a predetermined extent, an end portion carried by the feeler to prevent rotative movement of the feeler by engagement with the filling after it is unlocked until substantial exhaustion of the filling, and means for changing the operative condition of the loom when substantial exhaustion of filling permits rotative movement of the feeler on a detecting beat.
5. In a feeler motion for looms, the combination of a feeler, means for rotating the feeler, a lock to prevent rotative movement of the feeler until the latter enters the shuttle to a predetermined extent and then freeing the feeler to rotative movement, an end portion on the feeler to prevent rotative movement of the feeler by engagement with the filling after the feeler is unlocked until substantial exhaustion of filling, and means for initiating filling replenishment when upon substantial exhaustion of filling the feeler is rotated on a detecting beat.
6. In a feeler motion for looms, the combination of a feeler to enter the shuttle and feel for the filling, means for rotating the feeler, a lock to prevent rotation of the feeler and rendered ineffective on a detecting beat when the feeler enters the shuttle to a predetermined extent, a filling engaging end on the feeler to prevent rotative movement of the feeler by engagement with the filling on a detecting beat until substantial exhaustion of filling, and means actuated by the feeler when rotated to initiate filling replenishment.
7. In a feeler motion for looms, the combination of a feeler to feel for the filling in the shuttle and be moved forward as the lay beats up, means normally acting to rotate or rock the feeler about its longitudinal axis as it is moved forward, means for locking the feeler from rotative or rocking movement until the feeler enters the shuttle to a predetermined extent and then freeing the feeler to such rotative or rocking movement, a roughened or toothed end carried by the feeler to prevent rotative or rocking movement of the feeler by engagement with the filling on a detecting beat after the feeler is unlocked until the filling is substantially exhausted, and means for preventing rotative or rocking movement of the feeler when it is unlocked and in rearward position.
8. In a feeler motion for looms, the combination of a feeler to feel for the filling in the shuttle and be moved forward as the lay beats up, means tending to rotate the feeler when moved forward, means for locking the feeler from rotative movement adapted to be struck as the lay moves forward to unlock the feeler to rotative movement when the filling is exhausted a predetermined extent, a roughened portion carried by the feeler to prevent rotative movement of the feeler by engagement with the filling until substantial exhaustion thereof, and means for preventing rotative movement of the feeler when it is unlocked and in rearward position.
9. In a feeler motion for looms, the combination of a feeler, means tending to rotate the feeler on a detecting beat, a lock to prevent rotative movement of the feeler until the latter enters the shuttle to a predetermined extent and then freeing the feeler to rotative movement, a push member positioned for impingement and movement longitudinally by the feeler when the feeler is rotated on a detecting beat, and means actuated by the push member for initiating replenishment of filling.
10. In a feeler motion for looms, the combination of a feeler to feel for the filling in the shuttle and be given an indicating movement when the filling is substantially exhausted on a detecting beat, means for locking the feeler from substantial exhaustion indicating movement and freeing it to such movement when the filling has become exhausted to a predetermined amount, mechanism for initiating filling replenishment, a flexible member comprising an incased wire between the feeler and said mechanism adapted to be pushed by the feeler when the latter indicates substantial exhaustion of filling for effecting operation of said mechanism, and means for automatically resetting the feeler to initial locked position.
11. A feeler motion for looms, comprising, in combination, a feeler, means for rotating the feeler about its longitudinal axis, a lock for preventing rotative movement of the feeler until the filling has been exhausted to a predetermined extent, an end portion carried by the feeler to prevent rotative movement of the feeler by engagement with the filling after it is unlocked until substantial exhaustion of the filling, and means including a flexible push member positioned to be engaged and pushed lengthwise by the feeler for changing the operative condition of the loom when substantial exhaustion of filling permits rotative movement of the feeler on a detecting beat.
12. In a feeler motion for looms, the combination of a feeler, means tending to rotate the feeler on a detecting beat, a lock to pre-

vent rotative movement of the feeler until a predetermined amount of filling remains in the shuttle, a flexible push member having a part normally out of the path of movement of the feeler and adapted to be pushed by the feeler when moved from normal rotative position on the occurrence of substantial exhaustion of filling, and means operated by the flexible push member when moved by the feeler to initiate filling replenishment.

13. A feeler motion for looms, comprising, in combination, a feeler mounted for rotative movement, a lock mounted for longitudinal movement and acting to pre-

vent rotative movement of the feeler until the feeler enters the shuttle a predetermined amount, a flexible push member having a part normally out of the path of feeler movement when held from rotation by the lock and adapted to be moved longitudinally by the feeler when it indicates substantial exhaustion of filling, means controlled by the flexible push member for initiating replenishment of filling, and means for returning the feeler rotatably to locked position and automatically locking it. 20 25

In testimony whereof I have signed my name to this specification.

HARRY A. DAVIS.
